(57) **CLAIM**

The ornamental design for a dual pole power connector with hexagonal key center section, as shown and described.

DESCRIPTION

FIG. 1 is a top, front, and right side perspective view of the dual pole power connector with hexagonal key center section, showing our new design;

FIG. 2 is a front elevation view thereof;

FIG. 3 is a bottom plan view thereof;

FIG. 4 is a top plan view thereof;

FIG. 5 is a left side elevation view thereof;

FIG. 6 is a right side elevation view thereof;

FIG. 7 is a back elevation view thereof; and,

FIG. 8 is a bottom, back, and left side perspective view thereof.

The broken line showing on the drawing disclosure is for illustrative purposes only and forms no part of the claimed design.
